GAS MEASURING PROCESS AND APPARATUS

Harold Ashley Daynes, Cambridge, England

Application December 21, 1926, Serial No. 156,215, and in Great Britain January 22, 1926

8 Claims. (Cl. 23—232)

This invention relates to improvements in a method and means for measuring the amount of gas dissolved in a liquid and more particularly to the measurement of the percentage of oxygen dissolved in water.

It has been established that the corrosive properties of steam-boiler feed water are largely attributable to the oxygen dissolved therein and in many cases apparatus has been added to steam-generating installations for the purpose of removing or reducing the air or oxygen content of the feed water.

It becomes therefore a matter of importance that means should be provided for measuring the oxygen content for the purpose of checking the working of such de-aerating devices and for testing water from any source as to the percentage of dissolved air or oxygen.

The present invention consists in a method of determining the quantity of a gas dissolved in a liquid, which consists in selecting a second gas, scrubbing this second gas with the original gas-bearing liquid, and passing the scrubbed gas into or through one compartment of a known comparing device, whilst an untreated portion of said second gas is passed into or through the second compartment of the said comparing device.

The invention also consists in apparatus for carrying into effect the foregoing method.

One way of carrying the invention into effect will now be described with reference to the accompanying diagrammatic drawing.

The water to be tested flows through a pipe 1 to a constant head device 2 furnished with an overflow device 3 which by-passes excess water into the waste device 8. By this means a constant and unvarying stream of water flows through the pipe 4 and is distributed over a large number of small pieces of nickel, as shown, in a normal scrubbing device 5 and finally leaves the scrubbing device through a water seal 6 and thence through a pipe 7 to the waste device 8.

Pure hydrogen gas from an electrolytic device 10 is generated at the electrode 11 and passes up through a bell-shaped receiver 12 along a pipe 13. The pipe 13 has a T-connection 14, as shown, which allows the pure gas to have access to one chamber of a comparing device 21. The flow of gas continues through the pipes 15 and 16 to the lower gas space 17 of the scrubbing device 5. It then rises, in counterflow to the water to be tested, through the scrubbing device and emerges therefrom through

the pipe 18. A T-connection allows the treated gas to divide, part traveling upward along a pipe 20, so as to reach the other chamber of the comparing device 21 and the rest of the gas traveling downward, finally being discharged into the atmosphere through the pipe 22. The delivery of gas from the electrolytic device 10 is controlled in the usual manner by a variable resistance 23 acting on a source of current 24 and is checked by the meter 25.

The comparing device 21 is an instrument which depends for its operation on the difference of heat conductivity of two different gases. A suitable comparing device or catharometer is disclosed in British Letters Patent No. 124,453 to Shakespear.

In operation, a continuous definite flow of the water to be tested is passed through the constant level device to the scrubbing device 5. A measured continuous counterflow of pure hydrogen is simultaneously passed through the scrubbing device and in so doing sweeps out either a substantially fixed proportion or substantially the whole of the dissolved oxygen from the water, depending upon the design and the dimensions of the parts. The combined gas then escapes from the upper end of the scrubbing device to the atmosphere. One chamber of the comparing device or catharometer 21 is supplied with pure hydrogen and the other with the mixed gases from the scrubber. Suitable well-known indicating devices operated by the catharometer 21 will then indicate or record the varying percentages of oxygen in the mixed gases, which percentage, of course, may be translated into percentages of oxygen originally present in the water under test. In the event that a proportion only of the dissolved oxygen is swept out, the resulting measured value can easily be corrected for so as to yield the correct true value.

The device according to the present invention may be utilized for keeping a continuous record of the quality of boiler feed water as regards oxygen content and will serve to check the efficiency or to indicate any breakdown of the de-aerating plant.

It is to be understood that the present invention is not confined to the particular case of oxygen dissolved in water but applies to other gases and other liquids which fall within its scope.

I claim:

1. A method of determining the quantity of oxygen dissolved in water, which comprises

scrubbing the oxygen-containing water with hydrogen, passing a quantity of the scrubbed gas into one compartment of a gas-comparing device and a quantity of the original hydrogen into a second compartment of the gas-comparing device, and comparing the thermal conductivity of the gases in the compartments.

2. Apparatus for determining the quantity of a gas dissolved in a liquid towards which it is chemically inactive, comprising a scrubbing device, a gas-comparing device having two compartments, means for passing the gas-containing liquid through the scrubbing device, means for passing a second gas that is chemically inactive towards the liquid through the scrubbing device and into one of the compartments, and means for passing a quantity of the original second gas into the other compartment.

3. Apparatus for determining the quantity of gas dissolved in a liquid towards which it is chemically inactive, comprising a scrubbing device, a generator of a second gas that is chemically inactive towards the liquid, means for passing the gas-containing liquid through the scrubbing device, means for passing the second gas from the generator through the scrubbing device to scrub the first-named gas, means for controlling the flow of the gas-containing liquid through the scrubbing device, means for controlling the generation of the second gas in the generator, and means for determining the composition of the scrubbed gas.

4. Apparatus for determining the quantity of gas dissolved in a liquid towards which it is chemically inactive, comprising a scrubbing device, a gas analyzer, a generator of a second gas that is chemically inactive towards the liquid, means for passing the gas-containing liquid in one direction through the scrubbing device, means for passing the second gas from the generator through the scrubbing device in an opposite direction to scrub the first-named gas, means for passing the scrubbed gas into the gas analyzer, and means for passing a quantity of the original second gas into the original second gas into the gas analyzer.

tity of the original second gas into the gas analyzer.

5. Apparatus for determining the quantity of gas dissolved in a liquid towards which it is chemically inactive, comprising a scrubbing device, a generator of a second gas that is chemically inactive towards the liquid, means for passing the gas-containing liquid in one direction through the scrubbing device, a seal for the liquid leaving the scrubbing device, means for passing the second gas from the generator through the scrubbing device in an opposite direction to scrub the first-named gas, means for controlling the flow of the gas-containing liquid through the scrubbing device, means for controlling the generation of the second gas in the generator, and means for comparing a quantity of the scrubbed gas with a quantity of the original second gas.

6. A method of determining the quantity of a gas dissolved in a liquid towards which it is chemically inactive, which comprises scrubbing the gas-containing liquid with a second gas of different thermal conductivity that is chemically inactive towards the liquid, and comparing the thermal conductivity of a quantity of the scrubbed gas with the thermal conductivity of a quantity of the original second gas.

7. A method of treating gases that comprises scrubbing a liquid containing a first gas with a second gas of different thermal conductivity, and comparing the thermal conductivity of a quantity of the scrubbed gas with the thermal conductivity of a quantity of the original second gas.

8. A method of determining the quantity of oxygen dissolved in water, which comprises scrubbing the oxygen-containing water with hydrogen, and comparing the thermal conductivity of a quantity of the scrubbed gas with the thermal conductivity of a quantity of the original hydrogen.
